UNITED STATES PATENT OFFICE.

LOUIS A. NEMCOVSKY, OF NEW YORK, N. Y., ASSIGNOR TO VOICES, INCORPORATED, A CORPORATION OF DELAWARE.

SOUND PRODUCING AND CONTROLLING DEVICE.

Application filed August 18, 1922. Serial No. 582,585.

My present invention relates to sound producing and controlling devices, more particularly for toys such as dolls.

An object of the invention is to provide a device of the above character which shall be of low cost, both as to material and labor, which shall be durable in construction, and which shall in operation simulate faithfully the cry of a baby, calling ma-ma.

10 The invention is concerned with the type of sound producing mechanism in which the reed pipe has a lateral opening and in which the emission of air from the reed pipe is controlled by a slide valve action.

15 In order to produce more particularly the "ma" sound, it is important that the aperture in the reed pipe be opened quickly for forceful expulsion of the air. To this end I provide the reed pipe, in the preferred embodiment, with a circular aperture and the valve with a control tongue slidable with respect to said aperture and of diameter smaller than that of said aperture, so that in the relative longitudinal shift of the reed pipe 25 and the valve the aperture will be opened at a rate faster than the relative linear displacement of the parts.

In the preferred embodiment, the reed pipe is rigidly secured in the weighted head 30 of the bellows, so that it moves with said bellows in the collapse of the latter, the controlling valve being preferably stationary but mounted with sufficient freedom to be urged into firm operative coaction with said reed pipe by the expansion of a coil spring.

The above and other features of my invention may be fully understood from the accompanying drawings, in which are shown some of the various possible embodiments 40 of the invention.

In the accompanying drawings, Fig. 1 is a fragmentary view of the doll upon its back, with my mechanism in the interior thereof, the latter in side elevation.

45 Fig. 2 is a view similar to Fig. 1 showing the doll prone and the sound producing mechanism in longitudinal cross-section.

Fig. 3 is a sectional view taken along line 3-3 of Fig. 1 and on a larger scale.

50 Figs. 4 and 5 are fragmentary perspective views on a larger scale illustrating the operation of the valve, and

Fig. 6 is a perspective view of a modified form of valve.

55 Similar reference characters refer to sim-

ilar parts throughout the several views of the parts.

Referring to the drawings, there is shown in the interior of the doll 1 a preferred form of sound producing and controlling device, 60 comprising preferably a cylindrical casing 2, which may be of card-board, extending transversely from the front to the back of the doll. The casing is closed by a cover cap 4 near the front of the doll with a piece of netting 5 across the open end thereof, the sound escaping through an aperture 6 in the front of the doll.

Within the casing 2 and near the lower end thereof is mounted a bellows, the bottom of which 7 is secured as by glue within the lower end of the box 2 to constitute the bottom thereof. The bellows includes the usual circular collapsible wall 8 and has a weighted head 9, preferably of lead. Eccentrically of the weighted head is a reed pipe 10, which extends at right angles to the head and is preferably secured in place by forcing frictionally at its end into a corresponding aperture in the head 9.

The ordinary reed element is secured within the bellows end of the reed pipe, a fibre plug 12 being preferably forced into the reed pipe and having forced thereinto a reed element comprising a brass semi-cylindrical element 13 tapering to a point at its end as shown, and closed laterally by a vibrating reed 14, no part of the reed pipe extending beyond the inner surface of the weighted head. The opposite end of the reed pipe is closed by means of a fibre plug 15. The reed pipe has preferably a circular aperture 16 in its side through which the air forced from the bellows past the reed escapes to produce the sound.

The control member for opening and closing the circular aperture 16 comprises a valve plate member 17 with respect to which said reed pipe is slidable in operation, said valve plate being preferably mounted in substantially fixed position with sufficient freedom, however, to adapt itself readily for snugly contacting the reed pipe. In the preferred embodiment, a tube or rod 18 serves to sustain the valve, said tube extending axially through a sleeve or bushing 19 in the weighted head 9 and through the bellows and being secured as at 20 in the lower end 7 thereof. The valve plate 17 is preferably formed rigid with thimble 21, hav-

ing a reduced lug 22 jammed into a corresponding aperture in the valve plate, the thimble being telescoped over a finger 20 formed integral with rod 18 and extending 5 at right angles to the length thereof. In the preferred embodiment a small washer 23 encircles the finger 20 and is interposed between the main length of the rod 18 and the thimble 21, a coil spring 24 encircling 10 the thimble and exerting its pressure at one end against the washer 23 and at the other against the valve plate to urge it into firm coaction with the reed pipe. It is preferred to form the plate as a curved segment to 15 tightly engage the cylindrical reed pipe when pressed thereagainst by spring 24.

The valve preferably comprises an integral stamped metal plate in form of a frame having side members 25, an upper cross piece 26, and a lower cross piece 27, defining a frame aperture 28. The cross piece 26 is formed with an integral downwardly extending tongue 29, in the preferred embodiment, of a diameter somewhat smaller than 25 the diameter of the aperture 16 as best shown in Fig. 5, and a similar tongue 30 extends downward from the cross piece 27. Supporting thimble 20 for the valve, as shown, is preferably in the lower cross arm 30 27. The valve plate is preferably also formed with integral aligning tongues 31 formed as extensions of the side pieces 25 and extending toward each other for a substantial portion of the width of the plate, adding length and circumferential gripping area so as to prevent tilting or cocking of the relatively flat plate in operation.

The doll is operated as any ordinary speaking or mama doll of modern design. 10 The doll being first laid prone or upon its face, it will be seen that the weighted head of the bellows will drop to the position shown in Fig. 2, sucking in air through the usual check valve (not shown), the head sliding downward along rod 18 and the reed tube descending to position shown in which 15 part of the aperture 16 extends beyond the extreme or outer edge of the cross piece 26 of the valve. When the doll is now replaced upon its back, the weighted head 9 descends 20 toward the position shown in Fig. 1, drawing with it the reed tube as shown, the air from the bellows being forced past the reed through the reed tube for escape through 25 the aperture 16, whenever the latter is open. It will be seen that the air will first escape through the exposed segment of aperture 16, which becomes closed, or choked, as it passes the cross piece 26 of the valve plate but in 30 the continued descent of the reed tube the aperture 16 is quickly uncovered as the lower edge thereof passes the lower edge of tongue 27, the uncovering being at a rate materially quicker than that of the relative 35 linear displacement of the parts, by reason

of the reduced width of the tongue relative to the aperture, so that the syllable "ma" is distinctly enunciated. After the aperture 16 is completely uncovered the vowel sound is continued in the continued movement of 70 the aperture 16 from the lower end of the upper cross piece 26 to the upper end of the lower cross piece 27 until the lower cross piece again completely shuts off the escape of air from the reed pipe interrupting the 75 sound, which is, however, repeated by the identical operation when the lower tongue 29 slides past aperture 16 so that the syllable "ma" is repeated, the "ma-ma" sound being 80 thus realistically reproduced.

It will be seen that the mechanism is of particularly inexpensive and compact construction, comprising merely a lead plate, a rod which may be cut from ordinary wire stock, the ordinary reed pipe, a valve which 85 can be made by a simple stamping operation, and a thimble made by a simple screw machine operation. The assembly is particularly expeditious in that it involves merely punch press operations to combine 90 the bushing 19 and the reed pipe 10 with the lead head, the assembly of the valve plate 17 and rod 18 being effected by a simple manipulation without tools, special fastening 95 elements or adhesives of any kind.

In Fig. 6 is shown an alternative form of valve plate generally similar to that heretofore described but including a tongue 31 formed integrally with one of the side pieces 25 of the plate and having an aperture 32 therein, into which the finger 20 of the rod 18 heretofore described may be fitted, the latter being directly encircled by a coil spring similar to that shown at 24.

It will thus be seen that there is herein 105 described apparatus in which the several features of this invention are embodied, and which apparatus in its action attains the various objects of the invention and is well suited to meet the requirements of practical 110 use.

As many changes could be made in the 115 above construction, and many apparently widely different embodiments of this invention could be made without departing from the scope thereof, it is intended that all matter contained in the above description or shown in the accompanying drawings shall be interpreted as illustrative and not in a 120 limiting sense.

Having thus described my invention, what I claim as new and desire to secure by Letters Patent is:—

1. In a sound controlling device, in combination, a bellows having a movable head, a reed pipe rigidly secured with respect to said head and projecting in its path of movement eccentrically thereof and communicating with the interior of said bellows, said pipe having an aperture in one side, a 125

- rod extending through said bellows, a resiliently yieldable valve supported upon said rod, and slidably engaged with the apertured side of the reed pipe.
5. 2. In a sound producing and controlling device, in combination, a bellows having a stationary and a movable head, an apertured reed pipe secured eccentrically of said movable head and extending perpendicularly therefrom and in communication with the interior of said bellows, a rod extending axially of said bellows through said weighted head and secured to said stationary head, a valve plate, support means therefor at the 15 end of said rod, and spring means encircling said support means and resiliently holding said valve plate in operative coaction with said reed pipe.
3. In a sound controlling device in combination, a bellows including fixed and movable heads, an apertured reed pipe connected to one of the heads of said bellows, a support rod extending through said bellows, said support rod for the movable head having a portion extending at right angles to the length thereof, a valve plate supported by said portion, and spring means encircling said portion to urge said valve plate into operative coaction with said reed pipe.
25. 4. In a sound producing device, a bellows having fixed and movable heads, a sounding reed operated by the flow of air in the movement of the movable head in one direction and a chamber carried by the movable head receiving the sound from said reed having an emission aperture in its wall, a guide for the movable bellows head, and a control valve mounted on said guide in constant sliding contact with the wall of said chamber and cooperating with the sound emission aperture therein to control the emission of the sound.
30. 5. In a sound producing device, in combination, a reed pipe having an aperture in the cylindrical wall thereof, means for causing a flow of air through said reed pipe, and a control valve for said reed pipe slidably relative thereto to open and close said aperture, said control valve and said aperture having relatively different areas in proportions such as to uncover the aperture upon relative sliding of said elements at a rate faster than the rate of relative sliding.
35. 6. In a sound controlling device in combination, a reed pipe having a curvilinear aperture in the lateral wall thereof, a valve control element therefor having a curvilinear tongue of diameter smaller than that of said aperture, whereby upon relative movement of said reed pipe and said valve, said aperture will be uncovered at a rate faster than the relative linear movements of said elements.
40. 7. In a sound producing and controlling device in combination, a bellows, a reed pipe
- connected thereto, and in operative communication therewith, said reed pipe having a circular aperture near the free end thereof, a control valve for said reed pipe slidably longitudinally thereof, said control valve including a tongue of diameter smaller than that of said aperture, whereby the aperture will be uncovered in the relative sliding movement at a rate faster than the relative linear displacement of said elements.
45. 8. In a sound producing and controlling device in combination, a bellows, a reed pipe connected thereto, said reed pipe having a circular aperture near its upper end, a valve slidable longitudinally of said reed pipe, said valve comprising a plate in the form of a frame including upper and lower cross pieces, and a tongue extending from the upper and lower cross pieces thereof and sliding with said valve to cover and uncover said aperture, said tongue being of diameter smaller than the diameter of said aperture.
50. 9. In a sound producing and controlling device, in combination, a bellows having a weighted head, a reed pipe secured in said head in communication with the interior of said bellows and extending at right angles thereto eccentrically thereof, a valve plate slidable longitudinally with respect to said reed pipe for controlling the opening and closing of a circular aperture in the length of said reed pipe, support means for said valve, said support means comprising a rod extending axially of said bellows through said weighted head and secured near the opposite end thereof, spring means encircling a portion of said support rod to urge said valve into operative coaction with said reed pipe, said valve having a plurality of downwardly pointing tongues spaced from each other, each of said tongues of diameter somewhat smaller than the diameter of said circular aperture, said valve including guide portions to maintain it in firm operative coaction with relation to said reed pipe.
55. 10. A valve controlling member for sound producing devices, comprising a plate element in the form of a frame, including upper and lower cross pieces and an integral tongue extending downward from the upper cross piece thereof, a similar tongue extending downward from the lower cross piece thereof and integral tongue projections on said valve, said valve being curved to firmly contact the surface of a reed pipe.
60. 11. A valve controlling member for sound producing devices, comprising a plate element in the form of a frame, including upper and lower cross pieces, and an integral tongue extending downward from the upper cross piece thereof, a similar tongue extending downward from the lower cross

piece thereof and an integral tongue between the upper and lower cross pieces for attachment to a supporting member.

12. In a sound producing device, a bellows having fixed and movable heads, a sounding reed operated by the flow of air in the movement of the movable head in one direction and a chamber carried by the movable head receiving the sound from said 5 reed having an emission aperture in its wall, a guide for the movable bellows head, a valve member movably mounted on said

guide, and means cooperating with the valve member to move the same in one direction relative to the guide and constantly hold said member in slidale engagement with the wall of said sound chamber to cooperate with the sound emission aperture therein and control the emission of the sound. 15

Signed at New York in the county of New York and State of New York this 17th day of August, A. D. 1922.

LOUIS A. NEMCOVSKY.
